ICE TRAY

Dale C. Gerber, North Canton, Ohio, assignor to
 The Hoover Company, North Canton, Ohio, a
 corporation of Ohio

Application September 26, 1938, Serial No. 231,624

9 Claims. (Cl. 62—108.5)

This invention relates to refrigeration and more particularly to a freezing tray for domestic refrigerators having an indicator associated therewith to inform the user whether or not the tray is empty or full, and whether the contents are freezing or have become frozen.

When a freezing tray is positioned on the evaporator shelf of a refrigerator and the contents allowed to freeze, the tray also freezes to the evaporator shelf. Frequently ice trays are removed before the contents have been frozen and the tray is then returned to the shelf. This breaks the bond between the tray and the shelf. The tray and shelf then being dry, the tray will not freeze again to the evaporator shelf, resulting in a less efficient transfer of heat from the freezing contents of the tray to the evaporator shelf.

It is accordingly an object of this invention to provide a freezing tray in which it is not necessary to remove the tray from the evaporator shelf to determine if the contents have been frozen.

It is another object of this invention to provide a freezing tray having an indicator with means responsive to the condition of the contents of the tray to indicate the condition thereof.

It is another object of this invention to provide a freezing tray for a domestic refrigerator having a thermostatic element associated therewith adapted to be affected by the temperature of the material in the tray which operates a signal with indicia thereon to inform the user whether the contents of the tray is freezing or frozen.

Sometimes the tray is placed in the freezing compartment without being refilled. When ice is again needed none is available and it is necessary to refill the tray and wait until it has frozen.

It is accordingly another object of this invention to provide means to indicate whether the tray is full or empty which is visible when the cabinet door is opened to obtain foodstuffs so that the user is informed if the tray is empty every time the door is opened whereby the tray can be refilled before ice is needed.

It is another object of this invention to provide a freezing tray having means associated therewith affected by the weight of the receptacle and/or contents to operate a signal to inform the user whether the tray is full or empty.

It is another object of this invention to provide a freezing tray with means associated therewith to indicate whether the tray is full or empty, freezing or frozen, in which the indicating means is responsive to the condition of the contents of

the tray and is permanently associated with the tray.

Other objects and advantages of the invention will become apparent as the description proceeds when taken in connection with the accompanying drawing, in which:

Figure 1 is a longitudinal sectional view of a freezing tray with one embodiment of the invention applied thereto;

Figure 2 is a sectional view of a portion of the device of Figure 1 showing the indicating means in a position to indicate that the contents of the tray have become frozen;

Figure 3 is a front view of the device of Figure 1 partly broken away to show the indicating mechanism;

Figure 4 is a sectional view of another embodiment of the invention depicting the position of the indicating means when the tray is empty;

Figure 5 is a front view of the device of Figure 4 partly broken away to show the indicating mechanism, and

Figure 6 is a view of the device of Figure 4 depicting the position of the indicating means when the tray is full.

Referring to Figures 1, 2 and 3, 10 indicates a freezing tray adapted to be positioned on the evaporator shelf of a domestic refrigerator having a front wall 11 extending forwardly to form a handle 12. Secured in the front wall 11 is a bimetallic thermostatic disc 13 having a pin 14 secured thereto to contact a rocker arm 15 pivoted to bracket 16 mounted on cover member 17 which is riveted or otherwise secured to the front wall 11 of the tray. A torsion spring 18 surrounds the pivot pin for the rocker arm 15 and normally holds it in the position shown in Figure 1 with its outer end engaging a stop 19 on the bracket 16.

The cover member 17 is provided with an opening 20 so that the indicia of the front face of the rocker arm 15 will be visible therethrough. The rocker arm 15 has two front faces 21 and 22 each of which is marked with distinguishing indicia above referred to. These faces 21 and 22 may be painted in different colors or be provided with any distinguishing mark which will distinguish the one from the other, but it is preferable to mark the portion 21 with the word "freezing" and the portion 22 with the word "frozen".

A rubber member 23 is shown secured to the front of the tray so as to seal the interior of the tray from disc 13, and the latter is provided with a small opening 24 so that a vacuum will not be produced when the disc operates. The rubber

member may be omitted if desired and the disc secured in watertight engagement with the front of the tray.

In operation, the tray is filled with a substance to be frozen and placed on the evaporator shelf of a refrigerator and the substance allowed to freeze. When the contents have been frozen, thermostatic disc 13 will snap to the position shown in Figure 2 so that the pin 14 will engage the rocker arm 15 and move it into the position shown in Figure 2 against the action of the torsion spring 18.

If the user desires the frozen contents before they have been frozen, the rocker arm 15 will be in the position shown in Figure 1 and the word "freezing" will be visible through the opening 20 so that the user will immediately know that the contents have not yet frozen. If the rocker arm is in the position shown in Figure 2, the word "frozen" will be visible through the opening 20 and the user will know that the contents of the tray are frozen and ready for use.

As will be apparent from the foregoing, the device makes it unnecessary to remove the tray from the evaporator shelf, thereby breaking the bond between the tray and the shelf in order to determine if the contents of the tray have been frozen, but the condition of the contents of the tray can be readily determined by merely opening the cabinet door and glancing at the indicator.

The embodiment of Figures 4, 5 and 6 is similar to that just described except for a slightly different mounting for the temperature responsive means, and the addition of mechanism to indicate whether or not the tray is full or empty. The bracket 16' is provided with a slot 25 in which the pivot pin for the rocker arm 15' slides. The pivot pin is mounted through a member 26 having a portion 27 sliding in the bottom part of the cover 11'. The part 27 has a foot 28 to contact with the evaporator shelf 29 and a spring 30 surrounding it to normally hold it in its lowermost position.

The face 21' of the rocker arm 15' is provided with two distinctive markings, one above the other, preferably the upper marking is the word "empty", and the lower marking is the word "freezing". The face 22' of the rocker arm 15' has still a different distinguishing mark, preferably the word "frozen". Disc 13' is secured to the outside of the tray so that there will be no actual contact between the disc and the contents of the tray but the disc is made to be responsive to the temperature of the contents of the tray.

In operation, if the tray is not filled with water, the spring 30 will force the foot 28 down against the evaporator shelf 29 so as to raise the tray from the shelf and allow the rocker arm 15' to take the position shown in Figure 4 in which position the word "empty" is visible through the opening 20' and the user upon opening the refrigerator door will be immediately informed that the tray is empty whereby it can be refilled before the contents are needed. If the tray is full, the weight of the contents of the tray added to that of the tray will compress the spring 30 and move the rocker arm 15' to the position shown in Figure 6 so that the word "freezing" is visible through the opening 20'. The user will then know that the tray is full but the contents have not yet frozen. When the contents of the tray have become frozen, disc 13' will operate to move the rocker arm 15' to a position where the word "frozen" is visible through the opening 20'.

as described in connection with the embodiment of Figures 1 to 3, to inform the user that the contents have become frozen.

From the foregoing it can be seen that this invention provides a freezing tray with means permanently associated therewith to indicate whether the tray is full or empty or the contents freezing or frozen, which is simple in operation and simple and economical to manufacture.

While I have shown but two embodiments of my invention it is to be understood that these embodiments are to be taken as illustrative only and not in a limiting sense. I do not wish to be limited to the particular structure shown but to include all equivalent variations thereof except as limited by the scope of the claims.

I claim:

1. A freezing tray adapted to contain a material to be frozen in combination with means for indicating the condition of the material within said tray, and discernible indicia carried by said indicating means.

2. An ice tray adapted to contain water to be frozen, a thermostatic element positioned to be affected by the temperature of said water and signal means operated by said thermostatic element.

3. An ice tray adapted to contain water to be frozen, a thermostatic element positioned to be affected by the temperature of said water, signal means operated by said thermostatic element and additional means affected by the weight of water in said tray for operating said signal means.

4. A freezing tray for a domestic refrigerator adapted to contain a material to be frozen, in combination with means responsive to the condition of the material in said tray and indicia carrying means operable by said condition responsive means to indicate the condition of the material in said tray.

5. A freezing tray for a domestic refrigerator adapted to contain a material to be frozen, in combination with means responsive to the weight of material in said tray and means operable by said weight responsive means to indicate the amount of material in said tray.

6. A freezing tray for a domestic refrigerator adapted to contain a material to be frozen, in combination with means responsive to the thermal condition and weight of the material within said tray, and means operable by said thermal condition and weight responsive means to indicate the condition of the material in said tray.

7. A freezing tray for a domestic refrigerator adapted to contain a material to be frozen, means responsive to the weight of the material in said tray, said means comprising a reciprocating member mounted on said tray and a spring opposing the weight of the material therein, a member operatively connected to said reciprocating member, the second mentioned member having a plurality of indicia carrying portions, and means on the tray for covering and uncovering the indicia carrying portions as the reciprocating member moves.

8. An ice tray adapted to contain a material to be frozen, means responsive to the condition of the material within the tray, pivoted means carried by the tray and operable by said condition responsive means, said pivoted means having a plurality of indicia carrying portions, and means on the tray for covering and uncovering the indicia carrying portions as the condition responsive means operates.

9. An ice tray adapted to contain water to be frozen, a thermostatic element positioned to be affected by the temperature of said water, pivoted means carried by said tray and operatively related to said thermostatic element, said pivoted means having three indicia carrying portions, additional means affected by the weight of the water in the tray for operating said piv-

oted means, and means on the tray for covering and uncovering two of said indicia carrying portions when said thermostatic element operates and also for covering and uncovering two of said indicia carrying means when said additional means operates. 5

DALE C. GERBER.
